ANIMATED DISPLAY DEVICE

Douglas Heyes, Los Angeles, Calif., assignor to
Donald F. Duncan, Inc., Chicago, Ill., a corpora-
tion of Delaware

Application December 1, 1949, Serial No. 6,365

Term of patent 7 years

(Cl. D80—1)

To all whom it may concern:

Be it known that I, Douglas Heyes, a citizen of the United States, residing at Los Angeles, Los Angeles County, California, have invented a new, original, and ornamental Design for an Animated Display Device, of which the following is a specification, reference being had to the accompanying drawings, forming a part hereof.

Fig. 1 is a front perspective view of an animated display device, showing my new design;

Fig. 2 is a front perspective view showing the animated portion in an opposite position to Fig. 1; and

Fig. 3 is an end elevational view thereof.

I claim:

The ornamental design for an animated display device, as shown.

DOUGLAS HEYES.
